EXTENSIBLE DOLLY

Edward P. Allen, 99 Union St., Winooski, Vt. 05404

Filed May 17, 1966, Ser. No. 2,333

Term of patent 3½ years

(Cl. D14—3)

FIGURE 1 is a perspective view of an extensible dolly embodying my new design.

FIGURE 2 is a perspective view of an extensible dolly of my design shown erected at a first load-bearing level.

FIGURE 3 is a perspective view of an extensible dolly of my design shown erected at another load-bearing level.

FIGURE 4 is a side view of an extensible dolly of my design shown erected at still another load-bearing level, the vertical support member being fragmentarily shown for convenience of illustration.

I claim:

The ornamental design for an extensible dolly, as shown and described.
